UNITED STATES PATENT OFFICE.

ARTHUR S. TREW, OF PORTLAND, OREGON, ASSIGNOR TO TREW TABULATING MACHINE COMPANY, A CORPORATION OF OREGON.

MECHANICAL CARD-DISTRIBUTING MACHINE.

1,278,523.

Specification of Letters Patent. Patented Sept. 10, 1918.

Application filed December 18, 1915. Serial No. 66,548.

To all whom it may concern:

Be it known that I, ARTHUR S. TREW, a citizen of the United States, residing in the city of Portland, county of Multnomah, and 5 State of Oregon, have invented certain new and useful Improvements in Mechanical Card-Distributing Machines, of which the following is a specification.

My invention relates to improvements in 10 card distributing machines adapted for rapidly and accurately distributing cards, letters, and the like, from a container to a series of card receptacles, the main object of this invention being to provide a mechanically 15 operated machine, as distinguished from an electrically operated machine, shown and described in my pending application, filed February 4, 1915, Serial Number 6,159, or the pneumatically operated machine, shown 20 in my pending application, filed November 29, 1915, Serial Number 64,050.

Among the other objects of this invention are,—to provide in a card distributing machine of the character referred to, a continuously running ejector, held normally in a non-ejecting position, a continuously running card conveyer for transferring the cards from the card container, or holder, to a series of card receptacles, and a selecting 25 mechanism, with manually controlled means for moving the ejector into an ejecting position, and for setting the selecting mechanism, whereby, when a key, or lever, is moved by the operator, a card is ejected and 30 the selecting mechanism automatically and mechanically set for determining into which card receptacle the ejected card is to be deposited. Other novel features in card distributing machines will be referred to in connection with the following description of my 35 invention.

In order that others may clearly understand my invention, I have shown in the accompanying three sheets of drawings one 45 practical embodiment thereof, which I will now describe.

Figure 1 is a top plan view of a machine embodying my invention;

Fig. 2 is a vertical, longitudinal sectional 50 view through the machine on line 2—2 of Fig. 1;

Fig. 3 is a vertical cross sectional view on line 3—3 of Fig. 1;

Fig. 4 is a vertical cross sectional view on 55 line 4—4, of Figs. 1 and 2;

Fig. 5 is a top plan view of one of the selectors;

Fig. 5^a is an end view of the same;

Fig. 5^b is a detail sectional view on line 5^b of Fig. 5;

Fig. 6 is a longitudinal sectional view of the part shown in Fig. 5;

Fig. 6^a is a cross sectional view through said part on line 6^a—6^a of Fig. 6;

Fig. 7 is a vertical longitudinal sectional 65 view through a key box;

Fig. 7^a is a fragmentary sectional view showing a release key;

Fig. 8 is a fragmentary side view of a traveling conveyer chain, showing one of the 70 card propelling fingers;

Fig. 8^a is a top plan view thereof;

Fig. 9 is a fragmentary top plan view, partly in section, on an enlarged scale, showing the selecting mechanisms, the conveyer 75 and the key levers, taken on line 9—9 of Fig. 10;

Fig. 10 is a vertical sectional view on line 10—10, of Fig. 9, with the addition of two of the card receptacles in place; and

Fig. 11 shows one of the switch members 80 in the card receptacles.

Referring now more in detail to the drawings, the invention comprises a table-like structure having the legs 1—1, a lower shelf 2, an intermediate shelf structure 3, and a top frame 4. Mounted through the intermediate shelf 3, is a vertically disposed card holding box 5, provided therein with an elevator 6, having a spring supporting board 7, 85 upon which a stack of cards, letters, or the like, 8, rests within the box 5. The elevator 6, is provided at its bottom, at opposite sides, with pulleys 9—9, under which runs a supporting and elevating cable 10, one end of 90 which is attached near the top, at one side, of said card box, as at 10^a, and the other end of which runs over a pulley 11, at the opposite side of said card box, and is provided with a weight 12, whereby, as said weight 100 moves downwardly by gravity, it lifts the card elevator and the cards therein so that the topmost card is exposed in a position to be ejected horizontally from said card elevator, or card holder, in a manner herein- 95 after described.

An ejector plate 13, is pivotally mounted at its rear edge, as at 14—14, Figs. 2 and 9, said ejector plate being indicated in dotted lines in Fig. 9. The supporting and oper- 105

ating arms 15—15, extend slidably through standards or guide members 16—16, at opposite sides of the intermediate shelf 3, and at their forward ends they are connected by 5 means of links 17—17, to crank arms 18—18, upon the opposite ends of a shaft 19, mounted in suitable bearing standards 20—20, at opposite sides of the intermediate shelf 3, as clearly shown in Figs. 9 and 10. Mounted 10 upon said shaft 19, between its bearing standards 20—20, are two sprocket wheels 21—21, upon which run two sprocket chains 22—22, said sprocket chains passing over sprocket wheels 23—23, near the right hand end of 15 the table structure, and suitably supported in standards, as 24, Fig. 2, said sprocket conveyer chains extending thence downwardly through the intermediate shelf 3, and around sprockets, as 25, upon a shaft 26, suitably 20 supported underneath the intermediate shelf 3, as indicated in Fig. 2. A belt 27 operates over a pulley 28, upon the outer end of said shaft 26, and over a pulley 29, of a motor 30, supported upon the lower shelf 2. Thus 25 from said motor 30, through the belt 27, and the shaft 26, said conveyer sprocket chains 22—22 are driven. The sprocket chains are provided at spaces apart with conveyer fingers 22^a—22^a, and with selectors 31—31, said 30 selectors being shown in Figs. 5 and 6, in enlarged views, and each comprising a shaft or bolt 32, connected at its opposite ends with the spaced sprocket chains 22—22, said shaft or bolt 32, being provided with a longitudinal slot 32^a, and having mounted thereon a 35 plurality of cylindrical and ring members 33, 34, 35, 36, 37 and 38, the outer, or end, members 33 and 38, being relatively long, and provided in their outer ends with suitable 40 bearing end pieces as 33^a, and 38^a, and the members 34, 35, 36 and 37, being relatively short, ring-like members, spaced apart with cam washers 39—39, therebetween, each of said cam washers having a cam projection 45 39^a, a square portion 39^b, and provided with two locking notches or sockets, as 39^c and 39^d, Fig. 6^a, opening inwardly to its center. Slidably mounted in the slot 32^a, in the bolt or shaft 32, is a comb-like member 40, having 50 a projecting cam prong 40^a, and a series of short tooth-like portions 40^b—40^b, adapted to fit within the notches 39^c and 39^d, in the cam washers 39, so as to lock them against turning. When said comb-like member is shifted, as to the right in Fig. 6, said tooth-like 55 members 40^b, are moved to positions between said cam washers 39—39, and out of their notches, whereby to permit said cam washers to be turned upon the shaft, or bolt, 32, turning their cam portions 39^a, upwardly, as shown in Fig. 6^a. A spring 41, in the cylindrical member 38, of each selector, operates 60 normally to hold said comb-like member 40, to the left hand position, as shown in Fig. 6. 65 It will be noted that the cylindrical or ring-

like members 33, 34, 35, 36 and 37, each has projecting from its right hand side, Fig. 5, a lug-like member, as 33^a, 34^a, 35^a, 36^a and 37^a, adapted to fit in corresponding notches in the left hand sides of the adjacent ring 70 members 34, 35, 36, 37 and 38. These inter-fitting lug portions, or fingers, operate as spacers, and also as limits stops for the cam washers 39. There are two of these spacing lugs on each ring, at opposite sides, shown 75 in section in Fig. 6^a, in which lugs 34^a, are shown.

Said selectors are spaced between the sprocket chains 22—22, in the manner indicated in Figs. 2 and 10, of the drawings, one 80 of said selectors following close after each pair of conveyer fingers 22^a, upon said conveyer chains.

Mounted upon the intermediate shelf 3, at opposite sides thereof, are two upstanding 85 bearing supports 50—50, provided at their upper ends with forwardly projecting bearing members 50^a—50^a, which support the opposite ends of a shaft 51, as shown in Figs. 1, 2 and 10. Mounted upon the middle portion of said shaft 51, are two feed rollers 52—52, adapted to bear against two smaller feed rollers, as 53, supported upon a shaft 54, in short supporting arms 55—55, attached to the lower ends of two guide members 90 55^a—55^a. At their upper ends said guide members 55^a—55^a, are slidably mounted through the supports 50^a—50^a, as clearly indicated in Figs. 2 and 10, and near their lower ends, said guide members work 100 through guide blocks 50^b—50^b, attached to the members 50—50. Coiled springs 55^b—55^b, operate between projections on the sides of the members 50^a—50^a and 55—55, to yieldingly pull said short supporting arms 105 55—55, and the feed rollers 53 carried thereby upwardly, so that said feed rollers 53, are held in yielding bearing engagement with the feed rollers 52—52.

Said feed rollers 52 and 53, engage each 110 other in a plane corresponding to the plane of the topmost card in the card holder, whereby as said card is ejected, it is ejected so as to be caught between said rollers and fed forwardly thereby into a position to be 115 picked up by the next pair of conveyer fingers 22^a, on the conveyer chains 22—22.

Mounted upon the outer end of the shaft 51, which carries the larger feed rollers 52—52, is a gear 56 (Figs. 1, 3 and 10), which gear 120 meshes with a gear 57, on the shaft 19, and from which said gear 56 and the shaft 51, and the rollers 52, are driven, the shaft 19, as before described, being driven by the conveyer sprocket chains 22—22, which are 125 driven from the motor 30, through the belt 27.

The ejector plate 13, is normally held in a non-ejecting position, that is, so that it reciprocates above the topmost card in the 130

card holder, by means of two pivoted angle arms 58—58, the upper ends of which bear upwardly against the under side of said ejector plate 13. Coiled springs 59—59, normally tend to draw said ejector plate 13, downwardly, while stronger coiled springs 60—60, connected to the opposite, or lower, ends of said angle arms, normally hold their upper ends up in supporting positions under 10 the ejector plate and against the tension of the springs 59—59.

The lower ends of the two pivoted angle arms 58—58, are connected together by a cross member which has an off-set portion, 15 at 58^a, as indicated in Figs. 9 and 10, the front portion 58^b, of said off-set portion 58^a, constituting an upwardly projecting curved plate member, as clearly shown in Fig. 10. Said off-set portion 58^a, of said pivoted angle 20 arms is slightly narrower than the space between the conveyer chains 22—22, so as to allow the card conveyer fingers 22^a—22^a, on said chains to pass upwardly past the ends of said off-set portion, as indicated in Fig. 25 9, and said upwardly curved portion, or plate, 58^b, is so positioned that as a selector 31, moves upwardly, the cam portions 39^a, of the cam washers 39, engage said bearing plate 58^b, so as to overcome the tension of 30 the spring 60, and to raise the lower ends of the angle arms 58, sufficiently to move their upper ends downwardly and permit the ejector plate 13, to be drawn down into position to engage the topmost card, or letter, 35 in the card holder, and eject it horizontally between the feed rollers 52 and 53. The letter is thrown forwardly by the feed rollers after the selector 31, which has tripped the angle arms 58, as it is moved upwardly 40 past the same, and is caught by the conveyer fingers 22^a, upon the conveyer chains 22—22, and by them carried forwardly along the top plate 4, of the table structure, to the card receptacles, five of which are shown in Figs. 45 1 and 2, and designated, respectively, 61, 62, 63, 64 and 65, said receptacles constituting upstanding box-like structures open at their lower ends above the passageways for said cards, and provided with supporting plates, 50 as 61^a, 62^a, 63^a, 64^a and 65^a, said supporting plates being attached at one side of the box, or card receptacle, and projecting across the same for a portion of the breadth of the box and then curved downwardly, in the manner 55 clearly indicated in Figs. 1, 2 and 10.

Pivottally mounted in the open lower ends of said card receptacles are switch members, or plates, as 61^b, 62^b, 63^b, 64^b and 65^b, shown in perspective view in Fig. 11, said switch 60 members being pivoted near their tops, on a pivot rod, as 61^c, 62^c, 63^c, 64^c and 65^c. Secured to the pivot rod for each switch member, is a downwardly depending finger, as 61^d, 62^d, 63^d, 64^d and 65^d, said fingers being 65 differently positioned upon said rod, as

clearly indicated in dotted lines in Fig. 1, whereby to be engaged by different cam washers on the selectors 31. Secured to the opposite ends of the pivot rods for the switch members are depressing fingers 61^e, 62^e, 63^e, 70 64^e and 65^e, so that when the depending finger intermediate the ends of one of said switch rods is engaged by a selector washer, it will rotate said switch pivot rod, and through the depressing fingers tilt the 75 switch member downwardly, as indicated in Fig. 10, switch member 62^b. It will be apparent that it is necessary to form the switch members, as shown in Fig. 11, so as to give proper clearance for the card conveyer fingers 22^a, on the conveyer chain. It will be noted that the positions of the selectors 31, on the conveyer chains, relative to the conveyer fingers 22^a—22^a, are such that the selector will operate the proper switch in time 80 for it to catch the front edge of the card, or letter, being propelled by the following conveyer finger, whereupon the card or letter will be forced up over the switch member into the bottom of the card receptacle whose 85 switch member has been opened. Coiled springs 66, operate on the front ends of the switch members to normally hold them in closed positions.

I will next describe the mechanism by 90 means of which the selectors are controlled from a key box. Referring to Figs. 1, 7 and 9, a key box 70, is mounted in the front of the machine, provided with an intermediate horizontal partition member 71, Fig. 100 7. Mounted in said key box is a plurality of operating keys, 72, 73, 74, 75, 76 and 77, having their stems extending through the box and through the horizontal partition member 71, as clearly indicated in Fig. 7. 105 Each of the key stems is provided with a collar, as 78, against which bears a spring 79, the lower end of which spring rests upon the horizontal partition 71. Each of the key stems is provided immediately underneath said partition 71, with an off-set portion 80, which forms, at its upper edge, a shoulder bearing against the under side of said partition member 71, so as to limit the upward movement of said key stem. 110 Said off-set portion also terminates in a curved cam surface, as 81, the upper end of which ends in a projecting point 82, for a purpose hereinafter referred to. Each of said key stems is provided at its opposite 115 side with a projecting point, as 83, and near its lower end with a cam surface 84. A slide plate 85, is mounted in said key box and is normally held in one position by a coiled spring 86, as shown in Fig. 7. Said slide 120 plate is adapted to be moved forwardly when any one of the keys is pressed downwardly, by the engagement of the cam surface 81, of the key stem, with said slide plate, the openings through said slide plate 125 130

being sufficiently elongated to permit the key stem to be pushed down through said slide plate until the point 82, at the upper end of the cam surface 81, catches on the 5 under side of said slide plate. When said slide plate is moved forwardly by one key, it operates to lock the other keys against depression, for the reason that it moves underneath the projecting points 83, on the opposite side of the key stem. When a key is 10 pressed downwardly, its cam surface 84, engages the end of an operating lever, as 87, 88, 89, 90 and 91, which levers are of angle form, as clearly shown in Fig. 9, and 15 are pivoted, as at 92, upon a base plate 93, which extends between the bearing standards 20—20, as indicated on Fig. 9. The opposite end of said levers 87, 88, 89, 90 and 91, are turned at an angle and slidably 20 mounted through a guide plate, or member 94, preferably formed as a part of the base plate 93, which may also be formed as a part of the bearing standards 20—20. The ends of said key levers 87, 88, 89, 90 and 91, 25 normally project only slightly from said guide member 94, in alignment with the cam washers 39, of the selectors 31, so that when one of the keys is depressed, the end of its key lever is caused to be moved out- 30 wardly into the path of the square projecting portion 39^b, Fig. 10, of one of the cam washers of a selector 31, so that its cam portion 39^a, will be turned upwardly or outwardly from the carrying sprocket chain. 35 Any one of the cam washers when so turned will engage the off-set plate 58^b, of the angle arms 58, and lift them so as to permit the ejector plate to be lowered sufficiently to engage the topmost card, or letter, but the 40 set cam washer will only engage the proper switch member, by its depending finger, above referred to, in the bottom of the proper card receptacle, so as to set the switch member corresponding to the par- 45 ticular key depressed.

The guide member 94, has a cam extension 94^a, Figs. 5 and 5^b, positioned to engage the prong 40^a, on the comb 40, so as to move said comb to release said cam 50 washers at the time any one of them is engaged by the end of a key lever, as above described. Said prong 40^a, remains in engagement with said cam extension 94^a, long enough to unlock the cam washers and permit them to be turned, and then it is released and again locks the comb 40.

Each of the key levers 87, 88, 89, 90 and 91, are normally drawn back at their selector engaging ends, by means of a coiled 60 spring, as 93^a, as clearly indicated in Figs. 9 and 10.

Attached to the front edge of the slide plate 84, in the key box 70, is a link 95, connected to one end of a rocker arm 96,

pivoted upon a suitable supporting member, as at 97, the opposite end of which rocker lever 96, is looped around the path of the conveyer fingers 22^a, as at 98, Fig. 9, and then extended adjacent the path of the selectors 31—31, as they move upwardly 70 with the conveyer chains 22—22. When any one of the keys 72, 73, 74, 76 and 77, is depressed, the slide plate 85, will be moved forwardly in the key box, by the cam portion 81, of said key stem, as hereinbefore described, and will operate to rock the rocker arm 96, to move its opposite end slightly away from its position adjacent the path of the selectors 31, but not so far that it will not be engaged by the projecting cam 75 portion of any cam washer on a selector, by which said rocker lever 96, is moved to move said slide plate 85, to release the keys automatically. Key 75 is a release key and has no key lever extending therefrom, as will 80 be noticed in Figs. 1 and 9, but is provided with a cam member 75^a, Fig. 7^a, adapted to engage and move the slide plate 85, forwardly sufficiently to disengage the points 82, of any of the key stems which may be 90 down, and to permit them to be raised to their normal or up positions by their springs 79.

Referring to Figs. 2 and 4, there is mounted across the intermediate shelf structure 3, 95 a frame member 100, having an upper cross bar 101, with a downwardly projecting cam lug 102, and a lower cross bar 103, having an arch 104, formed therein, the downwardly projecting cam lug 102, being in position to 100 engage the projecting cam prong 40^a, on the comb member 40, of any one of the selector members 31, whereby to move said comb member so as to permit the cam washers of the selector member to be turned, while the 105 arched portion 104, engages the cam portions 39^a, of any of the selectors 31, and turns them to their normal, or inoperative, positions.

The operation of my card distributing 110 machine may be briefly described as follows: Assuming that the motor is running and is driving the conveyer 22 and the ejector 13, in the manner hereinbefore described, the operator by glancing at the topmost card in 115 the card box, which is exposed face up, is able to tell from the information thereon into which pocket said card goes, and presses the key corresponding to that pocket. Assuming that key 72 has been depressed, and key lever 87 has been moved upon its pivot 92, so that its free end projects from the guide plate 94, into position to engage the corner, or square portion, 39^b, of the cam washer, of the selector next to pass said 120 guide member 94, thereby turning said cam washer so that it projects outwardly from the conveyer chains, as indicated by 39^a, Fig. 125

10, and also seen in Fig. 9, it being the middle cam washer of the selector moving upwardly. At the time said key lever engages said cam washer, the cam extension 94^a, of 5 the guide plate 94, engages the cam prong 40^a, and moves the comb member 40 in the selector, in order to release, or unlock, said cam washers and permit the one engaged by the extended key lever to be turned. While 10 the other cam washers are also unlocked, they can not turn because their square, or straight, sides are moving along the ends of the other key levers. When the particular cam washer has been turned to the position 15 indicated, the comb is released and the cam washers are all again locked with the one in its turned or operative position.

Referring to Figs. 9 and 10, as said selector moves upwardly, it first engages the 20 rocker lever 96, and moves it so as to draw the slide plate 85, forwardly sufficiently to release the key 72, which has been depressed, and which is being held down by reason of the engagement of its point, or shoulder, 82, 25 against the under side of the slide plate 85. Said cam washer 39^a, next engages the curved plate 58^b, on the connecting extension 58^a, of the angle arms 58, and moves them so that the ejector plate 13, is drawn 30 downwardly by its spring 59, in position to engage and eject in a horizontal direction the topmost card. Said angle arms are held down sufficiently long by the engagement of the cam washer 39^a, with said curved plate 35 58^b, to permit a full stroke of the ejector, which ejects the topmost card between the feed rollers 52 and 53. The feed rollers throw the cards forwardly on the top plates 4, along the opposite sides of the machine, 40 and immediately following the selector, which has caused the operation of the ejector, and sufficiently forward so that the rear edge of the card, or letter, is engaged by the next transfer fingers 22^a—22^a, on the 45 conveyer chain, which operate to move said card, or letter, along with the conveyer. The cam washer, which is turned in operative position, moves along under the card receptacles until it engages the proper switch finger, which in this case would be 63^c, Fig. 1, 50 it being the middle cam washer, which finger it engages and thereby rocks the switch member down, in the position of switch member 62^b, Fig. 10, in time to catch the card, or letter, being pushed by the transfer fingers 22^a, whereupon said card, or letter, is pushed up into the bottom of the card receptacle, and underneath the stack which 55 would be resting upon the supporting plate in said pocket, or receptacle. As said selector moves on under the cross bar 101, Fig. 4, the lug 102, on said bar 101, engages the comb prong 40^a, of the selector and moves the comb to unlock the cam washers just as

the cam washer which has been operating, 65 engages the arch 104, on the cross bar 103, and is by it turned back into its normal position.

Thus I have provided in a card distributing machine, in combination with a card holder and a series of card receptacles, a continuously running card conveyer and a continuously running ejector, normally in a non-ejecting position, with selector mechanism and means for manually controlling 75 the same, whereby, when a key is depressed, a corresponding selector is set which causes the operation of the ejector and the setting of the proper switch for ejecting and transferring the card from the card container to 80 the pocket corresponding to the key depressed.

I am aware that many changes can be made in the details of construction of my invention as here illustrated, without departing from the spirit thereof, and I do not, therefore, limit my invention to the structural details here shown for purposes of illustration, except as I may be limited by the hereto appended claims. 90

I claim:

1. In a card distributing machine, in combination, a card holder, a series of card receiving pockets, a traveling conveyer for conveying cards from said card holder to 95 said pockets, switch members in said pockets for turning said cards into said pockets, an ejector reciprocating in a non-ejecting position adjacent said card holder, means for continuously driving said conveyer and 100 said ejector, and manually controlled selective mechanism for moving said ejector into a position to engage and eject a card from said card holder during its reciprocating movement and for setting the switch to a 105 selected pocket into which the ejected card is to be deposited.

2. In a card distributing machine, in combination, a card holder adapted to hold a stack of cards with the topmost card exposed to view, an ejector mounted to reciprocate across the top of said card holder for ejecting cards one by one horizontally therefrom, a series of receiving pockets for said cards, switch members for deflecting the 115 cards into said receiving pockets, a traveling conveyer adapted to receive the ejected cards and to transfer them to said pockets, means for continuously driving said conveyer and said ejector, a series of keys corresponding to said pockets, selective mechanisms carried by said conveyer and adapted to cause the movement of said ejector transversely of its reciprocating movement into a position to engage and eject the topmost 120 card, and to set a selected switch member, and operating connections from said keys 125 for setting said selective mechanisms,

3. In a card distributing machine, in combination, a card holder, adapted to hold a stack of cards, means for moving said stack of cards upwardly, an ejector mounted to reciprocate horizontally and continuously across the top of said card holder, means for so operating said ejector, a series of receiving pockets, a card conveyer mechanism for conveying the ejected cards to said pockets, and a key-controlled selective mechanism for moving the ejector at will to engage a card and pre-determining the pocket into which the ejected card is to be deposited.
4. In a card distributing machine of the character referred to, means for holding a vertical stack of cards with the topmost card exposed to view, a reciprocating ejector adapted to be moved at will into position to engage and eject the cards one by one horizontally from the top of said card holder, means for continuously reciprocating the same, feed rollers adapted to grip and feed the ejected cards forwardly in a horizontal direction, a traveling conveyer adapted to receive and carry said ejected cards, means for operating the same, a series of receiving pockets, switch members controlling the entrances to said receiving pockets, and manually controlled means for selecting and setting said switch members for directing the ejected cards into selected pockets and for moving said ejector into a card engaging position.
5. In a card distributing machine of the character referred to, a card holder, an ejector mounted to reciprocate in a non-ejecting position adjacent said card holder, means for continuously operating said ejector, manually controlled means for moving said ejector, during its reciprocating movement, into position to engage and eject the exposed card from said card container, and card conveying and distributing mechanism co-operating therewith and controlled by said manually controlled means, substantially as described.
6. In a card distributing machine of the character referred to, a card holder adapted to hold a vertical stack of cards, with the face of the topmost card exposed, means for feeding said stack of cards upwardly, an ejector mounted to reciprocate horizontally across the top of said card holder, in a non-ejecting position, means for continuously reciprocating said ejector, manually controlled means for moving said ejector into a position to engage and eject the topmost card from said card container, and card conveying and distributing mechanism co-operating therewith and controlled by said manually controlled means, substantially as described.
7. In a card distributing machine, in combination, a card holder, an ejector operable
- therein for ejecting cards therefrom one by one, a traveling conveyer, means for driving said traveling conveyer, a series of receiving pockets above said traveling conveyer, switch members in the lower open ends of said card receiving pockets, adapted to be moved into positions to pick up the cards carried by said traveling conveyer, and manually controlled selective mechanism for determining the switch member to be opened.
8. In a card distributing machine, in combination, a series of card receptacles open at their lower ends, switch members mounted in the lower ends thereof, a traveling conveyer mounted to travel under said receptacles and provided with card carrying means, and manually controlled selective mechanism for opening the switch in a desired receptacle for directing the card into said receptacle.
9. In a card distributing machine, in combination, a series of card receptacles, a traveling conveyer mounted to travel underneath said receptacles and provided with card carrying means, means for feeding cards to said conveyer one by one, switch members associated with said receptacles and adapted to direct cards from said conveyer into said receptacles, and manually controlled mechanism for selectively operating said switch members.
10. In a card distributing machine, in combination, a series of card receptacles, a traveling conveyer mounted to travel underneath said receptacles and provided with means for carrying cards, means for driving said conveyer, switch members associated with said receptacles and adapted to be moved into positions to direct cards from said conveyer to said receptacles, and manually controlled means for selectively operating said switch members.
11. In a card distributing machine, in combination, a series of card receptacles open at their lower ends, switch members movably mounted for directing cards into said receptacles, a traveling conveyer mounted to travel underneath said receptacles and provided with means for carrying cards, letters, and the like, means for driving said conveyer, selectors carried by said conveyer for operating said switch members, and manually controlled means for setting said selectors for selectively operating said switch members.
12. In a card distributing machine, in combination, a series of card receptacles open at their lower ends, switch members movably mounted for directing cards into said receptacles, a traveling conveyer mounted to travel underneath said receptacles and provided with means for carrying cards, letters, and the like, means for driving said conveyer, a card holder, means for ejecting cards therefrom, one by one, on to said conveyer, selectors carried by said conveyer for

operating said switch members, and manually controlled means for setting said selectors for selectively operating said switch members.

5 13. In a card distributing machine, in combination, a series of card receptacles open at their lower ends and provided with card supporting means therein, switch members movably mounted in said lower open ends 10 and adapted to be moved into position to direct cards up into said receptacles on to said supporting means, a traveling conveyer mounted to travel under said receptacles and provided with means for carrying cards, 15 means for driving said conveyer, and manually controlled means for feeding cards one by one to said conveyer and for selectively opening said switch members for directing the cards from said conveyer into said receptacles.

14. In a card distributing machine, in combination, a card holder adapted to hold the supply of cards, an ejector operable therein for ejecting cards therefrom, one by one, a 20 traveling conveyer adapted to receive and carry said ejected cards, a series of card receptacles having open sides adjacent said conveyer, switch members mounted in said receptacles and operable to direct cards from 25 said conveyer into said receptacles, selectors carried by said conveyer for operating said switch members, and manually controlled means for setting said selectors for operating the desired switch members, said selectors being adapted also to cause the operation of said ejector to eject the cards from 30 said card holder.

15. In a card distributing machine, in combination, a card holder adapted to hold a 40 stack of cards, letters, or the like, with the topmost one exposed to view, means for feeding said cards upwardly in said card holder, a horizontally operating ejector adapted to eject cards from the top of said 45 stack of cards, one by one, feed rolls for feeding the ejected cards forwardly, a traveling conveyer adapted to receive and carry said ejected cards, a series of card receptacles above said conveyer and provided with 50 switch members adapted to be moved to deflect cards from said conveyer into said receptacles, means for driving said conveyer and said feed rolls, selectors carried by said conveyers and adapted to be set to selectively 55 operate said switch members, and manually controlled means corresponding to said card receptacles for selectively setting said selectors, said selectors being adapted also to cause the intermittent operation of said 60 ejector, substantially as described.

16. In a card distributing machine, in combination, a card container, an ejector operable therein for ejecting cards therefrom one by one, a series of card receptacles, switch members for directing cards into said 65 receptacles, a traveling conveyer from said card container to said card receptacles adapted to receive and carry cards, selector mechanisms carried by said conveyer and adapted to be set to selectively operate said switch 70 members, manually controlled means for selectively setting said selector mechanisms, and means adapted to be engaged by said selector mechanisms for causing the operation of said ejector in ejecting the cards from 75 said container.

17. In a card distributing machine, in combination, a card container, an ejector operable therein for ejecting cards therefrom one by one, a series of card receptacles, 80 switch members for directing cards into said receptacles, a traveling conveyer from said card container to said card receptacles adapted to receive and carry cards, selector mechanisms carried by said conveyer and adapted to be set to selectively operate said switch members, manually controlled means for selectively setting said selector mechanisms, means for automatically restoring 85 said selector mechanisms to their inoperative position, and means adapted to be engaged by said selector mechanisms for causing the operation of said ejector in ejecting the cards from 90 said container.

18. In a card distributing machine, a card holder for holding a stack of cards, comprising a box-like structure, an elevator therein upon which said cards are carried with the topmost card exposed to view, means for gradually moving said elevator upwardly, an ejector operable horizontally across the top of said card holder, means for continuously operating said ejector in a non-ejecting position, manually controlled means for moving said ejector into position to engage and eject the topmost card from said card holder and card distributing mechanism for determining the disposition of said ejected cards, controlled by said manually controlled means.

19. In a card distributing machine, in combination with a card holder and a series of card receptacles, a reciprocating ejector adapted to be intermittently moved into position to eject cards, one by one, from said 115 card holder, a traveling conveyer provided with means for receiving and carrying ejected cards from said card holder to said card receptacles, means for driving said traveling conveyer and for reciprocating said 120 ejector, means carried by said conveyer for causing said ejector to be intermittently moved into position to engage and eject cards from said card holder, switch members for directing cards from said conveyer into said 125 receptacles, selectors carried by said conveyer for selectively operating said switch members, and means for setting said selectors during their course of travel to operate the desired switch members.

20. In a card distributing machine, a series of card receptacles open at their lower ends and provided with card supporting means, switch members mounted in the bottom of said receptacles and adapted to be moved to direct cards, letters, and the like, up into said receptacles and on to said supporting means, means for carrying cards along underneath said receptacles in position

to be engaged by said switch members, and 10 means for selectively operating said switch members.

Signed at Portland, Multnomah county, Oregon, this 4th day of December, 1915.

ARTHUR S. TREW.
